UNITED STATES PATENT OFFICE.

ROBESON B. WOLCOTT, OF CLEVELAND, OHIO, ASSIGNOR OF ONE-HALF TO JOSEPH N. BARRETT, OF CLEVELAND HEIGHTS, OHIO.

FUSE PLUG.

Application filed January 10, 1920. Serial No. 350,547.

To all whom it may concern:

Be it known that I, ROBESON B. WOLCOTT, a citizen of the United States, residing at Cleveland, in the county of Cuyahoga and State of Ohio, have invented a certain new and useful Improvement in Fuse Plugs, of which the following is a full, clear, concise, and exact description, reference being had to the accompanying drawings, forming a part of this specification.

My invention relates to fuse plugs and more particularly to a fuse plug which is adapted to fit the ordinary lamp socket which is used in house wiring circuits. Fuse plugs of this nature must be inexpensive and still must be strong and fire proof.

It is an object of the invention to provide a fuse plug which can be manufactured cheaply, which is strong and durable, which is neat in appearance and which can be readily inserted by any user.

There are on the market at the present day several different kinds of fuse plugs. One which is probably the most extensively used consists of a screw threaded plug which is adapted to fit the ordinary lamp sockets. These plugs have on their interior a conductor which will burn out and break the circuit when the current passing there-through is in excess of the amount intended for use in the circuit in which the plug is inserted.

Heretofore fuse plugs of the character above set forth have been constructed of porcelain or other similar material upon which porcelain was mounted the usual screw threaded shell which was adapted to engage the threaded socket. It is an important object of my invention to devise a fuse plug which may be made from the standard screw threaded metallic plug which is used in the manufacture of ordinary lamp bulbs. These standard plugs may be bought in the open market and at a low price. I use the standard plug and provide therefor an inexpensive, readily attachable transparent and close fitting cover member thereby reducing the expense of manufacture and still producing an efficient and fire proof fuse plug.

Other objects of the invention will be apparent from the detailed description of the device disclosed in the drawings accompanying this specification. In this specification and in the drawings I have disclosed

several forms which my invention may take, which forms are the best known to me at the present time. However, it is to be understood that by this specification and the accompanying drawings I do not intend to limit myself to the specific constructions disclosed as modifications in these structures may be required in the manufacture thereof or may occur to those skilled in this art. The real nature and scope of the invention disclosed is to be determined from the claims appended to this specification.

The same reference characters have been used to designate the same parts throughout the several views of the drawings in which—

Fig. 1 is a top plan view of my improved fuse plug with the cover member removed.

Fig. 2 is a bottom plan view of the cover member, a part of said member being shown in section in order to more clearly disclose the locking grooves formed therein.

Fig. 3 is a section taken on line 3—3 of Fig. 1 but showing the cover member in position on the shell.

Fig. 4 is a partial vertical section taken on line 4—4 of Fig. 1.

Fig. 5 is a horizontal section taken on line 5—5 of Fig. 3.

Fig. 6 is a detailed view showing how the glass supporting fingers and the locking fingers are formed on the edge of the body member.

Fig. 7 shows a slight modification.

Fig. 8 is a vertical section taken on line 8—8 of Fig. 7.

Fig. 9 is a top plan view of a modified form of fuse plug.

Fig. 10 is a partial vertical section taken on line 10—10 of Fig. 9.

Fig. 11 is a partial vertical section of a further modified form of the fuse plug.

Fig. 12 is a horizontal section taken on line 12—12 of Fig. 11.

Referring to the modification shown in Figs. 1 to 6, the reference numeral 13 designates the shell portion or body portion of the plug. This shell portion has a screw threaded plug portion 14 which is adapted to fit the ordinary lamp socket. The shell portion is provided with an inturned shoulder 15 at the plug end, which inturned shoulder is adapted to support the member 16 which completely closes that end of the shell. The member 16 may be made of

glass, wood, rubber, gutta percha or any composite material which is non-conducting. Imbedded in or otherwise secured to the member 16 is a metallic plate 17 which has a central opening therethrough to receive one end of the fuse 18. The end of the fuse is passed through the opening in the plate 17 and is then bent over against the plate and secured to the plate by means of solder 19. The fuse 18 extends upwardly in the shell as shown in the drawings and its upper end is securely connected to the shell portion 13 preferably by means of solder 20 as shown. The fuse 18 therefore constitutes a conductor extending from the plate 17 to the shell portion 13. The parts just described are substantially the same as the corresponding parts used on an ordinary incandescent lamp bulb. The shell portion 13, member 16 and plate 17 can be purchased in the open market at a very small cost. The fuse 18 can be readily attached as described above.

In order to make a fuse plug fire proof and to prevent accidents due to over charge a cover member is necessary for a fuse plug. This cover member must prevent the escape to fire and gases and must also be transparent so that the user can see whether or not the fuse 18 has been burned out. My improved fuse plug is closed by means of a cover member 21 which is shaped as shown in the drawings and whose inside diameter is substantially equal to the outside diameter of the upper end of the shell portion 13. The cover member will therefore tightly engage this end of the shell portion. The cover member is provided with an inwardly turned flange 22. Positioned beneath the flange 22 are two lugs 23 which are diametrically opposite each other as will be clear from Fig. 2. Formed in the cover member are notches 24 which are positioned 90° away from the lugs 23 as shown. The purpose of these notches will be later set forth.

Positioned within the cover member 21 is a transparent member 25 which I prefer to make of glass but which may be of insulating glass or any other suitable transparent material. This transparent member is supported on the upper end of the shell portion 13 by means of the lugs 23 referred to above and fingers 26 formed upon the upper edge of the shell portion in the following manner. Two parallel slits 27 are formed in the edge of the shell portion 13 as shown in Fig. 6. Two horizontally extending slits 28 extend from the lower ends of the slits 27 as will be clear from the drawings. The material between the slits 27 is bent inwardly at right angles to form the finger 26 shown in Fig. 1. There are two of these fingers as will be clear from the drawings. The fingers 26 are positioned between the notches 24 when

the cover member is placed upon the shell portion.

At points 90° distance from the fingers 26 slits 27 are formed in the edge of the shell portion but the slits 28 are omitted. The portion between the slits is then cut away instead of being bent inwardly as shown in Fig. 6. Notches 31 are therefore provided to receive the lugs 23 of the cover member. When the cover member is placed upon the shell portion the lugs 23 fit in the notches just described and the notches 24 are adjacent the edges of the fingers 26. Before the cover member is placed in position on the shell portion the transparent member 25 is positioned within the end of the shell portion wherein it will rest upon the two fingers 26. The cover member is then slipped onto the end of the shell and pressed downwardly until the lugs 23 engage the transparent member 25. The lugs 23 and fingers 26 being 90° apart cooperate to hold the transparent member in fixed position within the shell and prevent tilting of the transparent member. The lugs 23 prevent the flange 22 from coming in contact with the glass 25 hence a space 29 is left between the flange 22 and the glass 25. A suitable implement then may be inserted into this space beneath the flange in order to bend fingers 30 outwardly into the notches 24 as shown in Fig. 5. The fingers 30 point in opposite directions and engage the opposite sides of the material between the notches 24. The fingers 30 engaging in the notches 24 and the lugs 23 engaging in the notches 31 prevent the cover member from rotating on the shell portion and the fingers 30 prevent removal of the cover member from the shell portion. The cover member 21 may be of any suitable insulating material. Such material is inexpensive and inasmuch as the thin metallic shell 13 is also inexpensive the entire fuse plug can be cheaply made. The caps are preferably made from a compound commonly known as "hot molded insulation" but I also contemplate using a cold molded asbestos or electroplastic compound. The product "electroid" is also suitable. The transparent member 25 exposes the fuse 18 to view and the user can readily see whether or not the fuse has been burned out.

In the modification shown in Figs. 7 and 8 the parts are constructed substantially as described above except that fingers 30' are formed on the shell 13 and normally extend outwardly as shown. The cover member 21' is provided with notches 24' for the fingers 30'. When the cover member is positioned upon the shell portion the fingers 30' are bent inwardly toward each other. When the cover reaches the position wherein the lugs 23 engage the transparent member 25 the fingers 30' will spring outwardly.

again and engage the notches 24' of the cover member to securely lock the cover member in position on the shell.

In Figs. 9 and 10 I have shown a further modified form of my fuse plug. In this modification I provide a shell 32 which has its upper end spun outwardly to form a flange 33. At a plurality of points the flange 33 is slotted and the material between the slits is bent inwardly to provide fingers 34 which are adapted to support the transparent member 35. The fingers 34 are positioned slightly below the upper surface of the flange 33 so that the upper surface 15 of the transparent member 35 will be flush with the upper surface of the flange 33. By bending the fingers 34 inwardly notches 36 are formed in the flange 33. Three notches 36 and three fingers 34 are shown in the drawings but it will be apparent that this member may be modified at will.

Positioned beneath the flange 33 is a ring 37 made of any suitable insulating material. Positioned on top of the flange 33 is a ring 25 38 of the same insulating material. At points corresponding to the notches 36 the ring 38 is provided with depressed portions 39, which depressed portions fit into the notches 36 as will be clear from Fig. 30 10. Rivets 40 pass through the rings 37 and 38 and hold them in fixed relation to the flange 33. When the plug is inserted into the socket the operator will turn the plug by means of the rings 37 and 38. The depressed portions 39 fitting into the notches 36 prevent rotation of the rings 37 and 38 on the flange 33. The flange 33 is of slightly less diameter than the rings 37 and 38 as will be clear from Fig. 10. 40 so that there will be no danger of the user getting any electrical shock when inserting or removing a plug. The ring 38 is provided with an opening 41 of less diameter than the diameter of the transparent member 45 so that the ring 38 serves to hold the transparent member in position upon the fingers 34.

In the modification shown in Figs. 11 and 12 the shell 42 is substantially the same as the shell shown in Figs. 1 to 6 but on this shell there are four fingers 43 which correspond to the fingers 26 shown in Fig. 1 and there are four sets of fingers 44 which correspond to the fingers 30 shown in Fig. 5. 55 After the transparent member 45 is positioned upon the fingers 43 as shown in Fig. 11 the cover member 46 is cast or molded upon the shell portion 42. This provides a rigid unitary structure which is easy to make and cheap to manufacture and in which there can be no danger of the cover member becoming detached from the shell portion.

From what has been described above the construction and operation of my improved fuse plug will be apparent.

What I claim as new and desire to secure by United States Letters Patent is:

1. A fuse plug of the character described comprising a shell portion and a cover member provided with a recess in an inner wall, 70 and a finger formed on said shell portion to engage in the recess of the cover member to maintain the cover member in position upon said shell portion.

2. A fuse plug of the character described comprising a shell portion, a transparent member positioned within one end of the shell portion, a cover member provided with a recess in an inner wall thereof, and a finger formed on one end of said shell portion 75 to engage in the recess of the cover member for maintaining said cover member in position upon said transparent member.

3. A fuse plug of the character described comprising a tubular shell portion, a finger 85 formed on the end of said shell portion, an insulating cover member adapted to fit over and cover the end of said shell portion provided with a notch inside adapted to be engaged by said finger whereby said finger 90 maintains the cover member in position upon said shell portion.

4. A fuse plug comprising a tubular shell portion, inwardly turned fingers formed at one end of said shell portion back of the 95 edge, a transparent member loosely supported upon said fingers inside the shell, an insulation cap engaging said transparent member to hold it in position upon said fingers, and outwardly projecting means 100 formed on the edge of said shell portion for securing said insulation cap to said shell portion.

5. A device of the character described comprising a shell portion, notches and fingers formed on the edge of said shell portion, a cover member, lugs and notches formed on said cover member and a transparent member positioned upon said fingers, the parts being so constructed that 105 when the cover member is positioned on said shell portion the lugs on the cover member will engage in said notches on the shell portion, and the fingers on said shell portion will engage in the notches in said cover member. 110

6. A fuse plug comprising a tubular metallic shell having integral fingers turned inwardly from an edge thereof, a transparent cover resting upon the fingers inside the shell, and an integral insulation ringed cap secured over the periphery at the end of the shell engaging and holding the cover in place and insulatingly covering the entire end of the shell. 120

7. A fuse plug comprising a tubular shell having integral fingers turned inwardly from an edge thereof, a transparent cover resting upon the fingers inside the shell, a flanged cap secured over the end of the shell, 125 130

said cap having lugs on the inside of the flange to engage the cover so as to hold it in place.

8. A fuse plug comprising a threaded tubular shell having inwardly turned lugs sheared out of the wall thereof at an open end, a transparent cover resting upon the lugs to close the shell, and a flanged insula-

tion cap immovably secured over said end of the shell and covering the openings left in said shell at said lugs.

In witness whereof, I hereunto subscribe my name this 3rd day of January, A. D. 1919.

ROBESON B. WOLCOTT.
